UNITED STATES PATENT OFFICE

CARL E. STEWART, OF DETROIT, MICHIGAN

ENGINE VALVE

Application filed June 15, 1929. Serial No. 371,249.

My invention relates to engine valves, and more particularly to internal combustion engine valves of the poppet type.

One object of my present invention is to provide a valve actuating structure which may be automatically lubricated by connection with the usual pressure oil supply customarily provided in internal combustion engines for lubrication of crankshaft bearings, cylinder walls, etc.

A further object is to provide means for silencing the impact of push rod and valve stem during operation of the engine.

Another object is to provide a valve stem and push rod having complementally formed contacting end portions whereby the stem and rod may be maintained in coaxial alignment.

Other and further objects will be apparent from the description hereinafter of the invention in several forms of embodiment, which are illustrated in the accompanying drawings, in which the same reference characters indicate like parts in the several views, and wherein

Fig. 1 is a vertical section of part of an internal combustion engine block provided with one form of valve and valve operating means constructed in accordance with the present invention;

Fig. 2 is a perspective view of the form of push rod shown in Fig. 1;

Fig. 3 is a vertical section showing a modified form of valve stem; and

Fig. 4 is a vertical section of a further modified form of valve stem and push rod.

In the drawings, 1 designates generally a fragmentary section of an engine block, provided with a valve seat 2, in which is fitted a poppet valve 3 having the usual valve stem 4 which reciprocates in the valve stem guide 5. A coil spring 6, surrounding the valve stem 4 and compressed between one end of the guide 5 and a bearing 6', serves to maintain the valve normally seated. The valve is opened at appropriate periods in the cyclic operation of the engine by means of the arrangement of cam, tappet and push rod which will now be described.

The tappet 7, reciprocally mounted in the guide 8 at the lower part of the engine block

1, is provided with a cam follower shoe 9 which bears upon the usual engine-driven cam (not shown). In a screw-threaded socket 10 at the upper part of the tappet 7 is received the threaded shank 11 of a push rod 12 generally designated 12. The upper end of this push rod 12 engages the lower end of the valve stem 4, so that the push rod provides connection between the tappet and the valve stem to transmit the reciprocating motion of the tappet to the valve stem and thus periodically unseat the valve 3. In each of the modifications of my invention the engaging ends of valve stem and push rod are complementally configured with conical sockets and projections to effect a maximum bearing surface between the two members and to induce a tendency toward automatically maintaining the push rod and the valve stem in coaxial alignment. The complemental conical surfaces also provide a relatively large area for the reception of a lubricant, as will presently be described.

In the form shown in Fig. 1 the push rod 12 is conically recessed at 13, and the valve stem is conically extended at 14; while in the modification illustrated by Fig. 4 this arrangement is reversed, the push rod having a conical extension 13a, and the valve stem being provided with a complemental conical recess 14a.

It will be noted that in the forms of my invention shown in Figs. 1, 2 and 4, a special type of valve stem is employed, the end of the stem being specially formed to complement the coacting end of the push rod. In order to make the usual type of valve stem, which is provided with a plane circular end, available as an element in the combination which I have invented, I may provide a detachable fitting having a conical projection 14b, as shown in Fig. 3. A small set screw 14c serves to secure this fitting to the end of the valve stem.

The apex angle of the complemental conical surfaces employed in my invention may be of approximately any magnitude between say 20 and 160 degrees. I have obtained best results, however, and therefore prefer to use, 100

conical surfaces having an apex angle of about 60 degrees.

In each form of my present invention the push rod 12 is made adjustable axially of the tappet 7 through the medium of the polyhedral face 15 formed on the push rod, and the lock nut 16 engaged with the threaded shank 11 and adapted to bear against the upper end of the tappet 7. By means of this arrangement of parts, adjustment may be made whenever necessary, in an obvious manner.

To aid in silencing the operation of the parts hereinbefore described, and to prevent undue wear, I have provided a lubricating system which will now be described. An oil passage 17 penetrates the lower part of the block 1 and communicates at its outer end through a coupling 18 with the customary pressure oil supply of the engine. At its inner end the passage 17 communicates with a relatively narrow, vertical channel or slot 19 formed in the bore of the guide 8; and terminating in this channel 19 is a spiral groove 20 also formed in the bore of guide 8. The shank 11 of the push rod 12 is formed of such length that whatever may be its operatively adjusted position in the socket 10, a sump 21 will be left between the end 30 of the shank and the bottom of the socket. An annular groove 21' is provided in the tappet at such a level that the same will constantly communicate with the channel 19, whatever may be the relative positions of 35 channel and groove during normal operating reciprocation of the tappet. A short horizontal duct 22 places the sump 21 in communication with groove 21', and a vertical duct 23 axially of the push rod 12 places 40 the valve stem bearing surface of the latter in communication with the sump 21. In the form shown in Figs. 1, 2 and 3, where the push rod 12 is conically recessed, I have found it desirable to make the upper end of 45 the duct 23 slightly enlarged, as shown at 24, to provide a large amount of clearance for the apex of the conical end 14 of the valve stem 4, and in the modification of the invention illustrated in Fig. 4, where the 50 valve stem is conically recessed, a similar cavity 24a is formed in the valve stem for the same purpose.

It will be apparent that during operation of an engine provided with the device hereinbefore described, lubricating oil from the pressure supply will be forced through the system formed by the passage 17, channel 19, groove 21', horizontal duct 22, sump 21 and vertical duct 23, to lubricate the contacting 60 conical surfaces of the valve stem and push rod. The conical configuration of these surfaces of the valve stem and push rod provides a relatively large area for the reception of the lubricant and results in a greater 65 quantity of the lubricant being maintained

between the contacting surfaces of these two members than would be possible if the valve stem and push rod were provided with the usual plane contacting faces. The film of oil thus kept between the two surfaces has 70 been found exceedingly effective in minimizing the sound ordinarily caused by impact of the parts when not so lubricated. Moreover, some of the oil received by the channel 75 19 will travel down the spiral groove 20 to lubricate the reciprocating movement of the tappet 7 in its guide 8 and lessen the wear of these parts.

It will be apparent from the foregoing description and the accompanying drawings 80 that I have provided means for conducting a lubricant from a pressure supply to the contacting surfaces of tappet and guide, as well as valve stem and push rod, with the inevitable loss of effective tappet guide bearing surface reduced to a minimum.

It is to be understood that my present invention is capable of exemplification in other and further modifications not shown or described in this application for Letters Patent, but all such modifications insofar as they embody the principles of the present invention are to be deemed within the scope and purview of the appended claims.

What I claim and desire to secure by Letters Patent is:

1. The combination of a cam shaft, a valve stem, means interposed therebetween for transmitting movement from the shaft to the valve, said means having complementary tapered interfitting members and means for supplying fluid under pressure to the surfaces of said tapered members.

2. A tappet assembly comprising a base member adapted to be actuated by a cam, a second member adapted to actuate a valve, said members having complementary interfitting tapered portions, and means for supplying a fluid under pressure to the surfaces of said tapered portions.

3. A tappet assembly comprising a base member adapted to be actuated by a cam, said member having a tapered opening therein, a second member adapted to actuate a valve, said second member having a tapered portion fitting with said tapered opening and means for supplying fluid under pressure to the lower end of said tapered opening for passage to the surfaces of said tapered portions.

In testimony whereof I affix my signature.
CARL E. STEWART.
